UNITED STATES PATENT OFFICE.

CHARLES MURDOCK, OF NEW ROCHELLE, NEW YORK.

FIRE-ESCAPE BRACKET.

SPECIFICATION forming part of Letters Patent No. 293,191, dated February 5, 1884.

Application filed November 6, 1883. (No model.)

To all whom it may concern:

Be it known that I, CHARLES MURDOCK, of New Rochelle, in the county of Westchester and State of New York, have invented a new and Improved Fire-Escape Bracket, of which the following is a full, clear, and exact description.

My present invention relates to a bracket to be attached to the window-casing or wall of a building and used in connection with my new and improved fire-escape shown and described in Letters Patent granted to me July 31, 1883, and numbered 282,212; and the present invention consists in certain details of construction, as will be hereinafter fully described, and specifically set forth in the claims.

Reference is to be had to the accompanying drawings, forming part of this specification, in which similar letters of reference indicate corresponding parts in all the figures.

Figure 1 is a perspective view, showing the manner of using my new fire-escape bracket. Fig. 2 is a side elevation, showing the bracket in position for use. Fig. 3 is a sectional elevation of the window-casing and bracket folded to the position it will occupy when not in use, and Fig. 4 is a detailed face view of the step and lower section of the bracket.

A represents my improved bracket. It is composed of the main sections *a* *b*, hinged together, and the short plate *d*, to which the section *a* is hinged, and by which the bracket is secured to the window-casing *B* by the bolt *C* and nut *D*. The section *b* is formed near its upper end with the eye *f*, and in the center it is bent outward and recessed, as shown at *g*, to clear the step *h* and bolt *E*, and at the lower end it is beveled off, as shown at *i* *i*, to form the projection *i'*, which fits between the prongs *j* *j*, formed at the upper end of the step *h* when the bracket is arranged for use for securely holding the lower end of the section *b* against all lateral movement. The step *h* is bolted in proper position to the window-casing *B* by the said bolt *E* and the nut *F*, and at its upper end the step *h* is beveled inward and downward, as shown clearly in Figs. 2 and 3, for

receiving and securely holding the lower end of the section *b* upon the step, the position it will occupy when the bracket is arranged for use. When section *b* is placed upon step *h*, its upper end will be carried away from the wall of the building, bringing the section *a* into horizontal position and the eye *f* into proper position for receiving the hook of the fire-escape pulley *G*, as shown in Fig. 1, thus holding the pulley the necessary distance from the wall, to permit a person to descend by the escape-rope *H* without coming in contact with the wall; but when the section *b* is thrown off from the step *h*, the bracket will fold down close to the wall or window-casing, as shown in Fig. 3, where it will not in any manner disfigure the wall of the building.

I am aware that folding brackets are not broadly new, and I do not desire to claim such, broadly, as of my invention.

Having thus described my invention, what I claim as new, and desire to secure by Letters Patent, is—

1. A fire-escape bracket consisting of the securing-plate *d*, to which is hinged the short section *a*, carrying the section *b*, formed with an eye at its upper end, angular bend or recess near its middle portion, and a projection on its free end for engaging the step *h*, bolted to the window-casing, substantially as set forth.

2. In a folding bracket, the step *h*, beveled at its upper end, and formed with the inwardly-beveled projections *j* *j*, in combination with the section *b*, formed with the projection *i'*, and beveled portions *i*, for engaging the beveled projections *j* *j*, whereby all lateral movement of the section *b* is prevented, substantially as set forth.

3. In a folding bracket, the section *b*, bent in the center, as at *g*, to fold over the step *h*, substantially as herein shown and described.

CHARLES MURDOCK.
